UNITED STATES PATENT OFFICE.

MICHEL SCHAACK, OF CHICAGO, ILLINOIS.

WATER-HEATER.

SPECIFICATION forming part of Letters Patent No. 761,718, dated June 7, 1904.

Application filed September 21, 1903. Serial No. 174,060. (No model.)

To all whom it may concern:

Be it known that I, MICHEL SCHAACK, a citizen of the United States, residing at Chicago, in the county of Cook and State of Illinois, have invented certain new and useful Improvements in Water-Heaters; and I do hereby declare the following to be a full, clear, and exact description of the invention, such as will enable others skilled in the art to which it applies to make and use the same.

My invention relates to a novel construction in a water-heater, the object being to provide a cheap efficient device of this character; and it consists in the features of construction and combinations of parts hereinafter fully described and claimed.

In the accompanying drawings, illustrating my invention, Figure 1 is a central vertical section of a heater constructed in accordance with my invention, taken on the line 1 1 of Fig. 2. Figs. 2 and 3 are transverse sections of the same on the lines 2 2 and 3 3, respectively, of Fig. 1. Fig. 4 is a fragmentary detail section, on an enlarged scale, showing the joints between the various sections of my heater.

In the construction of water-heaters it is essential to provide a very large heating-surface in proportion to the volume of water and to provide for easy and rapid circulation of the contained water. To this end, and in order to render the construction of a water-heater of any desired capacity as cheap as possible without affecting its efficiency, I construct my heater mainly of a plurality of annular sections A, which are cast and correspond exactly with one another. Each of said sections or "units" A, as I shall hereinafter term them, consists, substantially, of two concentric annular water-chambers B and C, connected with each other at regular intervals at their upper ends by means of radial water-chambers D. Said water-chambers B and C are provided with corrugated inner walls forming annular flues between the same, while the spaces between the radial chambers D form corrugated vertical flues E, through which the products of combustion pass upwardly from the lower annular flues to the upper. Said units A are preferably constructed so that the

radial chambers D are of an odd number, preferably five, as herein shown, and the openings F and G, through which said units communicate with each other, are set at diametrically opposite points, so that in mounting 55 said units one over the other and turning each successive unit a half-turn relatively to the next lower unit the radial chambers D of each unit will be in vertical alinement with the vertical flues E of the next lower unit, so 60 that in passing upwardly the products of combustion will be obliged to take a zigzag course, and the greater part of the contained heat will be absorbed by the water. The openings F in the upper wall of each unit are bordered 65 by two concentric flanges H, between which packing I is contained and the annular flanges J, surrounding the openings G in the lower wall of the next succeeding unit, are received, thereby forming water-tight joints between 70 said units.

The upper and lowermost units K and L are modified in construction, said lowermost unit L consisting only of a single annular water-chamber M, corresponding in size and shape 75 with the chambers B of the units A and communicating with the latter, said chamber M being provided at its upper end with radial water-chambers N, between which are openings corresponding with the vertical flues E, 80 said water-chambers N being adapted to rest upon the upper wall O of the water-jacket P of the fire-pot in the base supporting said units.

In the uppermost unit K the water-chambers B and C are connected by the annular water-chamber Q, the vertical flues E being omitted. At one point said annular flue Q is provided with a passage for the reception of a flue R, connecting the heater with the chimney-flue S, said flue R being provided with a damper T. An opening is also provided through the annular flue B for the reception of the flue U, connecting with the central passage V of an annular water-chamber W, 95 mounted adjacent said units and inclosed in the lower end of said chimney-flue, said passage V forming a downdraft-flue connecting with the lower end of said chimney-flue, so that the products of combustion after pass- 100

- ing through said flue V will pass upwardly through the annular space X between the outer wall of said chamber W and the wall of the chimney-flue S.
- 5 The central passage Y in the units A, K, and L forms a storage or feed chamber for fuel to be fed to the fire-pot and is covered by the cover Z. The said central passage Y and the outer and upper walls of the heater 10 are lined with a non-conducting material, such as asbestos, to prevent radiation. The said heater is connected with the water-supply pipe a by means of the pipe b, entering the water-jacket N of the fire-pot, so that the cold water 15 is admitted at the point subjected to the greatest heat, and by means of a pipe c, entering the lower end of the annular chamber W. The latter is connected by pipes d and e with the lowermost unit A and the unit K, respectively, and the latter is connected by means of the pipe f with the service-pipes of the building or with a storage-tank for the hot water. The said water-jacket N is connected with the radial chambers of the unit L in the 25 same manner as the units A are connected with each other, and is further connected with the central chamber of said unit L by means of a pipe i. In order to hold said units together and compress the packings in the joints 30 between the same, the unit K and the base are provided with radial lugs g, between which the rods h are received, which are threaded at their ends to receive nuts in the usual manner, the latter engaging said lugs 35 to draw said units K and L toward each other. Heaters of various capacity can obviously be constructed as above by simply varying the number of said units A, while the latter by reason of being cast from the same pattern 40 and being comparatively light and small are readily transported and fitted together, thereby rendering the entire structure comparatively cheap. A test has demonstrated its great efficiency, as when the damper T is 45 closed, so that the products of combustion are forced to pass downwardly through the flue V, so much of their heat is absorbed as to enable the hand to be placed on the chimney-flue S without discomfort.
- 50 I claim as my invention—
1. In a water-heater, the combination with a
- heating-chamber and a chimney-flue, of a plurality of water-receiving units each comprising two concentric annular chambers connected at regular intervals by means of radial 55 chambers of less height, annular flues between said concentric water-chambers, and vertical flues between said radial chambers, said units being relatively so mounted that the radial chambers of each unit lie in vertical alignment with the vertical flues of the next adjacent unit, water connections between said units, and an upper unit consisting of an annular inverted U-shaped chamber provided with a vertical and a horizontal flue-opening 60 for connecting said annular and vertical flues of said first-named units with said chimney-flue.
2. In a water-heater, a unit comprising two concentric annular water-chambers and radial 70 chambers of less depth connecting said annular chambers, vertical flues interposed between said radial chambers, openings in the upper and lower walls of said annular chambers surrounded by annular flanges, said flanges surrounding the openings in the upper wall of said unit being adapted to interfit with the flanges surrounding the openings in the lower wall of the next higher unit, and packing interposed between said flanges and around said 75 openings.
3. In a water-heater, the combination with a fire-pot, of a plurality of separate annular water-chambers superimposed above said fire-pot and connected with each other and with 80 the water-service pipes of the building, annular flues interposed between said water-chambers, vertical flues relatively offset and connecting said annular flues, a chimney-flue, an annular water-chamber interposed therein, a 85 flue connecting said chimney-flue below said annular water-chamber therein with the upper end of said main water-heater, a flue connecting the latter with said chimney-flue above said water-chamber therein, and a damper in- 90 terposed in said last-named connection.
- In testimony whereof I affix my signature in presence of two witnesses.
- MICHEL SCHIAACK.
